UNITED STATES PATENT OFFICE.

CHARLES W. BARNABY, OF NEW YORK, N. Y.

TYPE-WRITER PLATEN.

1,226,626.

Specification of Letters Patent. Patented May 22, 1917.

Continuation in part of application Serial No. 791,335, filed September 23, 1913. This application filed May 5, 1916. Serial No. 95,612.

To all whom it may concern:

Be it known that I, CHARLES W. BARNABY, a citizen of the United States, and a resident of the borough of Richmond, county of Richmond, city and State of New York, have invented certain new and useful Improvements in Type-Writer Platens, of which the following is a specification.

My invention relates to means for mounting typewriter platens in their carriages and its primary object is to provide a platen of improved construction which does not limit the width of the sheet upon which the writing is to be recorded. Another object is to provide improved line-spacing mechanism for typewriter platens of this character. A further object is to reduce the length of space occupied by the platen and its mountings below what is required for those of the usual construction. Other and further objects will appear in the specification and be pointed out in the claims, reference being had to the accompanying drawings, which exemplify my invention in its adaptation to a typewriter similar to that shown in my application for patent on type-writing machines, Serial Number 667,537, filed December 23, 1911. The present application constitutes in part a divisional application of my copending application Ser. No. 791,335, filed September 23, 1913.

Figure 1 is a front elevation of the typewriter carriage, shown but not claimed in my copending application Serial No. 791,335;

Fig. 2 is an end elevation of the same taken from the right of Fig. 1, with the hand grip removed;

Fig. 3 is a vertical, longitudinal section of another embodiment of my invention viewed from the front;

Fig. 4 is an end view and part section of Fig. 3 viewed from the right;

Fig. 5 is a front elevation of a further embodiment of my invention, partly broken away at the left end;

Fig. 6 is an end elevation of Fig. 5 viewed from the right and partly broken away;

Fig. 7 is a vertical, horizontal section of still another embodiment of my invention viewed from the front;

Fig. 8 is an end view, partly in section, of Fig. 7, viewed from the right.

Generally stated, my invention consists of an open end platen and a plurality of rollers mounted in a carriage in such a manner as to provide for the passage of various thicknesses of paper around the platen and between the engaging peripheries of the platen and rollers, without disturbing the parallel axial alinement of the platen with respect to the carriage in which it is mounted. This I prefer to accomplish by so mounting the platen and rollers in the carriage that the relative distance between their axes may vary according to the differences in thickness of the materials inserted between them.

In the embodiments of my invention shown on the drawings, the carriage frame comprises a plurality of longitudinal members 1 and 2 and a pair of laterally spaced end frames 3 which are rigidly secured to said longitudinal members. In Figs. 3 to 8 inclusive, another longitudinal member 15 is included in the carriage frame. Member 15 partly encircles the platen and is carried up at the right end 16 to partly inclose the end of the platen. The member 1 is provided with a roller 4 journaled on the screw 5. A rack bar 6 is also rigidly secured to the ends of the end frames 3 and constitutes one of the longitudinal members of the carriage frame. Journaled within the end frames 3, or in flexing arms pivoted within said end frames are a plurality of rollers 7 and 8, the former being disposed to the rear and the latter to the front of a platen 9. The sheet to be written upon passes between the periphery of the platen and rollers 7 and 8 and is still further held in contact with the platen by means of spring clips 31, or by means of spring members 13, according to Figs. 5 and 6, said members being provided at their upper ends with pins 12 upon which are pivoted rollers 11 which contact with the sheet operated upon.

In the embodiment of my invention shown in Figs. 1 and 2, the rollers 7 and 8 are pivoted in fixed bearings in the end frames 3. The right hand end frame 3 is provided with a standard 28 provided with an opening to receive the platen axle 27. The platen 9 having no pivot at its left hand end is dependent for its alinement upon the rollers 7 and 8 upon which it rests, being held in

contact with said rollers by its weight and also by means of the pressure upon its top exerted by the spring clips 31. I prefer to give the platen axis 27 sufficient freedom in its opening in standard 28 to prevent it from coming in contact with the same under usual operating conditions. This makes the alinement of the platen entirely dependent upon its contact with the rollers 7 and 8 and when sheets of paper are passed between the platen and rollers, the freedom of motion allowed about the pivot 27 allows the platen to rise slightly more or less to accommodate the thickness of the sheets inserted. The rolls being pivoted in fixed bearings, will obviously maintain the platen axis in its same parallel relation to the carriage. The paper may be fed by means of the hand grip 30, or by means of some usual form of line spacing lever provided with a pawl to engage the teeth of ratchet wheel 29. It is obvious that in this application of my invention, the sheet passed around the platen cannot extend farther toward the right hand of the carriage than the left face of the ratchet wheel or of the line spacing lever and pawl operating it. The attachments of the platen and carriage would therefore extend beyond the right hand edge of the sheet by the amount of space taken up by the line spacing lever and attachments, ratchet wheel 29, axle pivot 27 and hand grip 30. The left hand of the carriage being open the sheet may extend any required amount beyond the left hand end of platen 9. When, as in the case of portable machines, a minimum space is desirable beyond what is necessary for the actual working length of the platen, I prefer to employ one of the applications of my invention exemplified in Figs. 3 to 8 inclusive.

Referring to Figs. 3 and 4, carriage frame 15 is closed at one end by the wall 16 (shown better in Figs. 5 and 6 which are similar in this respect), and from this wall 16, there extends a portion 17 within the end of platen 9. This extension 17 carries a hub 18 which carries the line spacing lever 32 and it also receives the sleeve 21 which acts as a pivot for the platen, being attached to disk 20 which in turn is secured to the inner circumference of the platen body. The line spacing lever 32 carries a pawl 33 which engages ratchet teeth 10 cut into the inner circumference of the platen body. The top of wall 16 and inner extension 17 is cut away to a sufficient extent to allow room for the line spacing lever 32 which latter may therefore be of the same thickness at its outer end and placed in the same plane as the face of wall 16. When the line spacing lever is in its normal position as shown, lug 61 of lever 32 (shown partly broken away), strikes the upper edge of 17 forming a stop for said lever. The tail 35 of pawl 33 also strikes

the upper edge of 17 and throws the pawl out of engagement with the ratchet teeth 10 which permits the platen to be rotated in either direction by means of the hand grip 25. When the outer end of the line spacing lever is pressed upward, the pressure on tail 35 is removed and the pawl is thrown into engagement by the action of the pawl spring 37. The line spacing lever is thrown upward until it is stopped by the stop lug 38 which will occur when the platen has rotated to the extent of one ratchet tooth. Lug 38 is attached to a member 57 passing around the inside of 17. Member 57 is provided with a pin 39 which engages a hole in 17. Another hole is located farther down at 40. By pressing lug 38 inward, the pin 39 is disengaged with the hole, as shown in Fig. 6, when, by pressing downward on the lug 38, member 57 may be shifted so that the pin will engage hole 40. The line spacing lever 32 may now be thrown farther to the position 32', Fig. 8, which will rotate the platen to the extent of two ratchet teeth and when the lever is thrown back to normal position 32, lug 61 and tail 35 will strike the edge of 17 as before and the pawl again will be thrown out of engagement, as shown by the dotted position of pawl, Fig. 8.

Referring to Figs. 3 and 4, member 57 is slotted to make room for spring 58 which is secured to 17 by screw 60. Loop 59 at the free end of the spring passes through an opening provided in 17, and acts as a dog to engage the ratchet teeth for locating the platen in the proper line space position.

The hand grip 25 is attached to shaft 24 which is provided with a pin 26 which engages the walls of a slot 22 in sleeve 21, whereby any rotative motion applied to 25 is transmitted to the platen. When not in use, hand grip 25 may be pushed into the dotted position, flush with the faces of 16 and 32, which reduces the device to a minimum space when the typewriting machine is placed in its case. Nut 23 performs triple service: first, it retains the platen pivot sleeve in its proper relation to its bearing in 17, second, it retains lever 32 in its proper place, and third, acts as a stop for pin 26 when hand grip 25 is drawn out into working position.

In this case, Figs. 3 and 4, the platen pivot 21 may fit snugly in its bearing in 17. In this case roller 8 is pivoted at each end in a lever 41, each lever 41 being rigidly attached to shaft 42 which is pivoted at each end in the end frames 3. Likewise roller 7 is pivoted in levers 43 secured to shaft 44. Springs 49 at each end of the carriage keep the rollers pressed against the platen. Platen pivot 21 keeps the right hand end of the platen in proper place and the rollers being located by their contact with the pivot end of the platen will, through the rigidity

of the shafts 42 and 44, properly support and locate the left hand end of the platen. When a sheet of paper is passed around the platen, the rollers 7 and 8 are merely swung 5 out slightly farther from the platen, the platen remaining in the same position as before. If it is desired to have the two rollers act in unison, an arm 46 may be attached to each shaft and connected together 10 by the link 45, as indicated by the dotted lines, Fig. 4.

Referring to Figs. 5 and 6, the application 15 of my invention as here shown is practically the same as in the preceding case, with the exception that there is only one through shaft 42 to which the two levers 41 are securely attached. Each of the levers 41 is provided with a second arm 46 which is connected by two links 45 with the two levers 47. The two levers 47 are connected 20 independently to an end frame 3 at each end of the carriage, but the two levers 47, in which roller 7 is pivoted, are compelled to move in unison with each other and also 25 with respect to levers 41 through their connection with these levers by means of the links 45. The action is therefore similar to that of the preceding case.

Referring to Figs. 7 and 8, the application 30 of my invention here shown is similar in many respects to Figs. 3, 4, 5 and 6, the line spacing mechanism is substantially similar and the carriage in general is substantially similar. The carriage frame 15, 16, and 17 35 is the same with the exception that the hub is different, having a long extension 19 which supports the left hand end of the carriage. The left hand end of the platen is provided with a sleeve pivot 52 which has a bearing in the end of the extended hub 19. A member 53 has a hook extension which 40 passes through an opening in the end of the platen and engages a flange in the outer end of hub extension 19 to prevent the platen 45 from moving off of its bearings toward the left. The other end of said platen is pivoted on hub 19 by means of disk 51. The stem 24' of hand grip 25 has a groove 54 in its left hand end to engage a pin 55 secured 50 in the pivot sleeve 52. The head of screw 56 screwed into the end of stem 24' engages pin 55 to prevent hand grip 25 from being drawn out beyond the proper working distance.

55 As the hand grip 25 is adjustable to a point within the plane of wall 16, and as there is no obstruction at the right hand of the platen and sheet of paper which it carries until they strike wall 16, it is obvious 60 that the platen carriage and mountings only need be about the thickness of wall 16 beyond the required length of the platen.

As the platen is pivoted at both ends and its proper alinement thereby assured, I prefer in this case to use elastically hung rollers,

each end of each roller being pivoted in separate links 48 separately pivoted on pivots 50 carried by the end frames 3.

I claim:—

1. In a machine of the character described, 70 the combination of a platen provided with a journal on one end, said platen being open at its other end, and means for rotatably supporting the open end of said platen.

2. In a machine of the character described, 75 the combination of a platen provided with a journal on one end, said platen being open at its other end, and means for rotatably supporting the open end of said 80 platen, said means comprising rollers journaled on fixed axes and in peripheral contact with said platen.

3. In a machine of the character described, 85 the combination with a carriage provided with a bracket at one end, of a platen journaled at one end in said bracket, said platen being open at its other end, and paper holding means for rotatably supporting the open end of said platen. 90

4. In a machine of the character described, 95 the combination with a carriage provided with a bracket at one end, of a platen journaled at one end in said bracket, said platen being open at its other end, and paper holding means for rotatably supporting the open end of said platen, the journal of said platen having play within its bearing in said end bracket.

5. In a machine of the character described, 100 a carriage, a platen journaled only at one end in a portion of said carriage, and rolls peripherally supporting and constraining said platen to rotate about the axis of its journaled end. 105

6. In a machine of the character described, 110 a platen, a carriage therefor open at one end and closed at the other, said platen having one end journaled in the closed end of said carriage, and means supported from the closed end of said carriage for journaling the other end of said platen.

7. In a machine of the character described, 115 a platen, a carriage therefor open at one end and closed at the other, said platen having one end journaled in the closed end of said carriage, and means supported from the closed end of said carriage for journaling the other end of said platen, said means extending within said platen. 120

8. In a machine of the character described, 125 a carriage open at one end and closed at the other, the closed end of said carriage being provided with an elongated bearing extending to a point adjacent to the other end of said carriage, and a platen journaled in said elongated bearing.

9. In a machine of the character described, 130 a carriage, a platen journaled thereon, said platen being provided with a recessed end

- wall and said carriage being provided with a bearing offset into said recess, line-spacing means mounted within said recess in the end wall of the platen, and means for rotatably supporting the other end of said platen.
10. In a machine of the character described, a carriage, a platen journaled thereon, said platen being provided with a recessed end wall and said carriage being provided with a bearing offset into said recess, line-spacing means mounted within said recess in the end wall of the platen, and means for rotatably supporting the other end of said platen, said line-spacing mechanism including an annular ratchet on the overhanging circumferential wall of said platen, and a ratchet pawl coöperating therewith.
11. In a machine of the character described, a carriage, a platen journaled thereon, said platen being provided with a recessed end wall and said carriage being provided with a bearing offset into said recess, line-spacing means mounted within said recess in the end wall of the platen, and means for rotatably supporting the other end of said platen, said line-spacing mechanism including an annular ratchet on the overhanging circumferential wall of said platen, and a ratchet pawl coöperating therewith, said pawl being journaled on said bearing.
12. In a machine of the character described, a carriage open at one end and closed at the other, the closed end thereof being deflected inwardly, and carrying a bearing, a platen journaled in said bearing, said platen having an open end extending over and around the inwardly deflected end wall of said carriage, ratchet line-spacing mechanism within said open end of the platen, and yieldable means interengaging between the deflected end wall of said carriage and the end of said platen to retain the platen in predetermined line-spacing location.
13. In a machine of the character described, a carriage open at one end and closed at the other, the closed end thereof being deflected inwardly, and carrying a bearing, a platen journaled in said bearing, said platen having an open end extending over and around the inwardly deflected end wall of said carriage, ratchet line-spacing mechanism within said open end of the platen, and yieldable means interengaging between the deflected end wall of said carriage and the end of said platen to retain the platen in predetermined line-spacing location, said yieldable means being mounted on the inner wall of the inwardly deflected end wall of said carriage and extending through an opening in said end wall.
14. In a machine of the character described, a carriage open at one end and closed at the other, the closed end thereof being deflected inwardly, and carrying a bearing, a platen journaled in said bearing, said platen having an open end extending over and around the inwardly deflected end wall of said carriage, ratchet line-spacing mechanism within said open end of the platen, and yieldable means interengaging between the deflected end wall of said carriage and the end of said platen to retain the platen in predetermined line-spacing location, said yieldable means comprising a leaf spring mounted on the inner circumferential wall of the inwardly deflected end wall of said carriage extending through an opening in said end wall, and engaging a part rigidly mounted on the inner circumferential wall of said platen.
15. In a machine of the character described, a carriage having an inwardly deflected portion at one end, a platen extending over and around said inwardly deflected portion and having one end journaled therein, line-spacing mechanism mounted within the end of said platen, a line-spacing lever extending outwardly from said mechanism but inside the plane of the end of said carriage.
16. In a machine of the character described, a carriage, a platen, rollers peripherally supporting and centering said platen, and a rigid element movable about an axis parallel to the axis of said platen and carrying one of said rollers.
17. In a machine of the character described, a carriage, a platen, rollers peripherally supporting said platen, and rigid elements for carrying said rollers, said elements being movable about axes parallel to the axis of said platen, said elements being connected by a link to constrain them to unison in movement.
18. In a machine of the character described, a carriage, a platen, rollers peripherally supporting said platen, and rigid elements for carrying said rollers, said elements being movable about axes parallel to the axis of said platen, one of said rollers being suitably connected to another of said rollers to produce parallelism in the movement of said rollers.
19. In a machine of the character described, the combination with a platen, of a carriage within which said platen is journaled and a telescopic handle movable into and out of a position between the end planes of said carriage.
20. In a machine of the character described, a carriage, a platen rotatable about an axis, rollers peripherally supporting and centering said platen, and means for mounting said rollers to swing about axes parallel to the axis of said platen.
21. In a machine of the character described,

- scribed, a carriage, a platen rotatable about an axis, rollers peripherally supporting and centering said platen, and means for mounting said rollers to swing about axes parallel to the axis of said platen, a pair of said rollers being connected by a link to constrain them to unison in movement.
22. In a machine of the character described, a carriage, a platen rotatable about an axis, rollers peripherally supporting and centering said platen, and means for swinging said rollers about axes parallel to the axis of said platen, one of said rollers being suitably connected to another of said rollers to produce parallelism in the movement of said rollers.
23. In a machine of the character described, the combination with a carriage, of a platen suitably connected at one end to said carriage to rotate about a movable axis, said platen being open at its other end, and paper holding means for rotatably supporting and centering said platen.
24. In a machine of the character described, a carriage having an inwardly deflected portion at one end, a platen journaled in and extending over and around said inwardly deflected portion, and line-spacing mechanism including a line-spacing lever journaled within the end of said platen.
25. In a machine of the character described, a carriage having an inwardly deflected portion at one end, a platen journaled in and extending around said inwardly deflected portion, and line-spacing mechanism including a line-spacing lever journaled within the end of said platen, said inwardly deflected portion of said carriage being broken away on one side to accommodate a portion of said line-spacing mechanism which connects said lever to said platen.
26. In a machine of the character described, a carriage having an inwardly deflected portion at one end, a platen journaled in and extending around said inwardly deflected portion, and line-spacing mechanism including a line-spacing lever journaled within the end of said platen, said inwardly deflected portion of said carriage being broken away on one side to accommodate a portion of said line-spacing mechanism which connects said lever to said platen, said line-spacing lever being provided with a radially extending portion within the end of said platen and an offset radially extending portion projecting beyond the periphery of said platen.
27. In a machine of the character described, a platen provided with a journal disposed inside of one end thereof, a carriage having a bearing for said journal disposed inside that end of the platen and a line-spacing lever provided with a hub por-
- tion journaled within said end of the platen and provided with operating connections with said platen within said end thereof.
28. In a machine of the character described, a platen provided with a journal disposed inside of one end thereof, a carriage having a bearing for said journal disposed inside that end of the platen and a line-spacing lever provided with a hub portion journaled within said end of the platen and provided with operating connections with said platen within said end thereof, said carriage being provided with an end wall deflected inwardly into said end of the platen and having a portion thereof broken away around the operating connections between said line-spacing lever and platen.
29. In a typewriting machine, a carriage, a bracket, a platen journaled at one end in said bracket, ratchet mechanism within the journaled end of said platen for imparting line-spacing movements thereto, and a line-spacing lever having a portion thereof disposed within the end of said platen.
30. In a typewriting machine, a carriage, a bracket carried thereby, a platen journaled at one end in said bracket, said bracket having a wall transverse to the axis of said platen, ratchet mechanism disposed within the journaled end of said platen and between the end planes of said platen, and a line-spacing lever comprising a portion operably connected to said ratchet mechanism and disposed within and between the ends of said platen and another portion projecting radially and in line with the transverse wall of said bracket.
31. In a typewriter, a carriage, provided with a transversely extending portion adjacent one end and with an extension to said portion displaced inwardly with respect to said portion, a platen journaled at one end in said extension, and line-spacing mechanism disposed between said extension and the outer face of the said transversely extending portion.
32. In a typewriter, a carriage, provided with a transversely extending portion adjacent one end and with an extension to said portion displaced inwardly with respect to said portion, a platen journaled at one end in said extension, and line-spacing mechanism disposed between said extension and the outer face of said transversely extending portion, said line-spacing mechanism including a lever arm projecting transversely to said platen and in line with said transversely extending portion.
33. In a machine of the character described, a carriage provided with an end wall, a platen, and a line-spacing lever extending beyond the periphery of said platen and substantially flush with said end wall.
34. In a typewriting machine, a carriage provided at one end with a transverse wall,

a platen journaled in said wall, and line-spacing mechanism including a line-spacing lever having a portion extending beyond the periphery of said platen and substantially flush with said transverse wall.

35. In a typewriting machine, a carriage having at one end a transversely arranged portion provided with a bearing extending inwardly from a plane adjacent to the end of said platen, a platen journaled in said bearing and line-spacing mechanism including a line-spacing lever having a portion extending beyond the outer periphery of said platen in substantial alinement with said transversely arranged portion.

36. In a typewriting machine, a carriage having at one end a transversely arranged portion provided with a bearing extending inwardly from a plane adjacent to the end of

said platen, a platen journaled in said bearing and a line-spacing mechanism including a line-spacing lever having a portion extending beyond the outer periphery of said platen in substantial alinement with said transversely arranged portion, said transversely arranged portion being deflected inwardly around the peripheral edge of said platen to accommodate portions of the line-spacing mechanism.

37. In a machine of the character described, a carriage provided with a transverse end wall, a platen journaled in said carriage, and a line-spacing lever having a portion thereof adjacent to the periphery of said platen, arranged flush with said end wall.

CHARLES W. BARNABY.
